UNITED STATES PATENT OFFICE.

PRESCOTT C. WILSON, OF BROOKLYN, NEW YORK.

TRAVELING SAIL-SECURING DEVICE.

Application filed February 10, 1927. Serial No. 167,346.

This invention relates to improvements in securing devices of the type wherein the part secured thereby is restrained for traveling movement along a definite course, and being adapted for various applications. More particularly in some of its aspects the invention relates to improvements in traveling securing devices for securing sails or the like for traveling movement along a spar or mast.

10 It is the general object of the invention to provide an improved securing device of the class mentioned, so constructed and arranged as to diminish or practically overcome tendency to jamming or binding or other obstruction to the free traveling movement of the securing device.

20 A further and more particular object of the invention is to provide an improved securing device of the class mentioned in which a plurality of spaced point contacts are provided between a runner or traveler slide and its supporting guideway, so as to decrease the tendency to binding or jamming of the runner in its movement in either direction along the guideway.

25 A further object is to provide an improved device for securing a sail or the like to a mast or spar so as to attain greater freedom of hoisting or lowering movement thereof and to minimize the time and effort required to raise or lower the sails.

Still another object of the invention is to provide an improved automatically shifting attachment for attaching a sail or the like 30 to a runner so as to automatically free the runner from binding tendency during movement thereof in either direction.

Other objects will be in part pointed out below in connection with the detailed description 35 of an illustrative but preferred embodiment of the invention, and will be in part obvious in connection with said description.

The invention accordingly comprises the features of construction, combinations of elements, and arrangement of parts, which will be exemplified in the articles hereinafter described and the scope of the application of which will be indicated in the claims.

For a more complete understanding of the 40 nature and objects of the invention, reference is had to the following detailed description

of the illustrative embodiment of the invention and to the accompanying drawings, in which:

Fig. 1 is a fragmentary elevation showing 55 a sail attached to a mast by a securing mechanism embodying the invention.

Fig. 2 is an enlarged perspective view with parts broken away for clearness of disclosure, showing a traveling slide or runner embody- 60 ing the invention.

Fig. 3 is a sectional plan, and

Fig. 4 is an elevation with certain parts broken away showing the cooperation of the runner with a supporting guideway. 65

For the purpose of furnishing a detailed disclosure of the invention, an embodiment thereof is shown in the drawing as applied to the support of a sail to a mast or spar for movement therealong in either direction as 70 during raising or lowering of the sail.

Referring to the drawing for a detailed disclosure of the embodiment of the invention there shown, a sail 10 of a sailing vessel is supported by a spar or mast 11 which may 75 be positioned as desired. A guideway 12 in the form of an elongated flat bar or plate is secured to the mast by suitable securing devices 13, its direction of length corresponding generally with that of the mast. A supporting block or strip 14 may be interposed between the guideway and the mast so as to provide a firm seat for the bar and to space it slightly from the adjacent surface of the mast. 85

A plurality of traveler slides or runners 15 are mounted for slidable engagement with the guideway in connected relation therewith, each runner being provided with an attaching bar 16 secured at longitudinally 90 spaced parts thereof to the runner as by studs 17, preferably integral with the runner. As shown, these studs are preferably bowed to form loops extending beyond or forwardly of the adjacent ends of the runner and forming 95 terminal seats 18, each positioned in advance of the adjacent end of the runner. The attaching bar extends longitudinally of the runner and is spaced slightly therefrom so as to provide an elongated slot or passageway 100 for the reception of an attaching ring or link 19, which is thus movable longitudinally rel-

atively to the runner, such movement being limited by the terminals or seats 18 of the slot. Each attaching link is connected to the sail in any desired manner, the connection preferably including a reinforced eye 20 secured to the sail.

All of the runners 15 are of the same construction, and a description of one only is a description of all. As shown in Figs. 2 and 10 3, the runner is generally channel-shaped in cross section, including a back section 21, opposed side or edge sections 22 and opposed inwardly extending marginal projections or flanges 23. This construction provides opposed edge channels or grooves 24 for the reception of the edges of the guide bar, as shown in Fig. 3. The slide or runner is thus connected to the guideway for traveling movement in either direction therealong.

20 The bottom of the edge channels of the runner form edge contact surfaces 25 for co-operation with the adjacent contact surfaces of the guide bar 12, said contact surfaces 25 being curved or convexed longitudinally 25 from end to end thereof, and also convexed or rounded transversely so as to present dome-like contact surface at any point therealong for providing a point contact cooperative with the opposed edge contact surfaces of the 30 guide bar 12. The contact surfaces 25 are so disposed and the curvature thereof so proportioned relatively to the width of the guide bar 12 that whenever contact occurs between the cooperating surfaces such contact will be 35 within the longitudinal limits of the contact surfaces 25 and will always be a point contact. For example, as clearly seen in Fig. 4, when the runner tilts edgewise in either direction, the engagement between the guideway edges and the convex contact surfaces 25 occurs within the longitudinal limits of the latter no matter what may be the degree of 40 tilting. In Fig. 4 the runner is tilted or rotated as far as possible to the left and the 45 contact points 26 between the runner contact surfaces 25 and those of the bar 12 are well within the longitudinal limits of said contact surfaces 25.

The result of this arrangement is that the 50 contact surfaces 25 are always brought into play whenever an engagement occurs with the edges of the guide bar 12. Furthermore, due to the longitudinal and transverse curvature of the contact surfaces 25, the contact thereof 55 with the guide bar will always be a point contact. Frictional resistances to progress of the runner in either direction is thus materially reduced and tendency to binding or jamming action between the runner and guide 60 bar is diminished. Also engagement between any flat angular or sharp surfaces of the runner with the guideway is prevented.

Frictional or other resistance to the progress of the runner along the guideway is still 65 further decreased by the dome-like contact

surfaces 27 formed on the inner face of the back section 21. The contact surfaces 27 are preferably positioned at or near each end of the runner and arranged transversely thereof, being convexed longitudinally thereof in a 70 direction transverse to the runner and also convexed or rounded transversely of their length, thus forming contact surfaces similar in form to contact surfaces 25. The contact surfaces 27, therefore, always contact with 75 the adjacent face of the guide bar at a point, and a dome-like surface is always presented to the guide bar, even though the runner may tilt slightly transversely of its length. The inner surfaces of the side sections 28 of the 80 back 21 may also, if desired, be similarly provided with contact surfaces similar to contact surfaces 27, but arranged longitudinally of the runner, and each presenting a dome-like point contact intermediate the ends of 85 the runner. Furthermore, the inner surfaces of the flanges 23 are provided with contact surfaces 29 being convexed inwardly longitudinally thereof and longitudinally of the 90 runner, and being also convexed or rounded transversely thereof, as seen in Fig. 3, so as to provide a dome-like contact surface similar to the other contact surfaces above described and adapted to form a point contact with the 95 adjacent face of the guide bar 12.

From the foregoing it will be seen that the runner is provided at all parts thereof which oppose and make contact with any part of the guide bar during travel therealong in either direction, with the dome-like contact surfaces, each contacting at a point only with the adjacent surface of the guide bar. Resistances to progress of the runner in either direction is, therefore, reduced to a minimum and tendency to binding or jamming is diminished, both by the dome-like contact surfaces and by the arrangement of the edge contact surfaces 25, as above set forth.

Binding or jamming tendency of the runner is still further diminished by the lost motion connection between the link 19 and the runner provided by the elongated connecting bar 16, with the end extensions thereof, and link seats 18 positioned beyond the adjacent contact surfaces of the runner at 115 either end thereof, as above set forth. With this arrangement any incipient binding or jamming that may occur is immediately freed by operation of this connection, due to the fact that any longitudinal stress exerted upon the runner by the connecting link 18 is directed in the form of a pull at a point beyond the advance contact surfaces of the runner in either direction of travel thereof. A longitudinal pull upon the runner directed as described tends to bring it into alignment with the guide bar, thus minimizing binding tendency due to tilting of the runner.

Since certain changes may be made in the above construction, and different embodi- 130

ments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A traveler slide for securing devices having a plurality of angularly disposed faces, each provided with one or more dome-like projections providing point contact surfaces.

2. A traveler slide for securing devices having opposed similar longitudinally and transversely curved contact edge surfaces, and having opposed surfaces disposed at an angle to said edge surfaces, and each provided with one or more point contact surfaces.

3. In a device of the character described, in combination, guideway and a runner slidably supported by said guideway and having point contact therewith at a plurality of angularly disposed faces thereof.

4. In a device of the character described, in combination, an elongated guide bar having a plurality of angularly disposed contact surfaces and a runner having projecting dome-like surfaces providing point contacts in sliding supporting engagement, respectively, with said angularly disposed contact surfaces.

5. In a device of the character described, in combination, a guideway and a runner having similar oppositely disposed longitudinally and transversely convexed edge contact surfaces, each of said contact surfaces being longitudinally convexed throughout its longitudinal extent.

6. In a device of the character described, in combination, a guideway and a runner slidably supported by said guideway and having point contact therewith at a plurality of angularly disposed faces thereof, and a connecting link connected to said runner for shifting movement longitudinally thereof in either direction.

7. In a device of the character described, in combination, an elongated guide bar having a plurality of angularly disposed contact surfaces, a runner having projecting dome-like surfaces providing point contacts in sliding supporting engagement, respectively, with said angularly disposed contact surfaces, and a connecting link connected to said runner for shifting movement longitudinally thereof in either direction.

8. In a device of the character described,

in combination, a guideway and a runner having similar oppositely disposed longitudinally and transversely convexed edge contact surfaces, each of said contact surfaces being longitudinally convexed at both end contact parts thereof, and a connecting link having a shifting point of connection with said runner shiftable to points in advance of the foremost of said contact surfaces when the traveler is moved in either direction.

9. A runner for securing devices having supporting contact surfaces and having a longitudinally extending connecting bar fixed in longitudinal position upon the runner, said bar having a loop at each end thereof providing link receiving seats positioned in advance of the respective adjacent contact surface.

10. In a device of the character described, in combination, a guideway, a runner connected to the guideway for movement therewith, a connecting link for said runner connected to the latter, the connection between said runner and connecting link including seats at either end of the runner and fixed in position relatively to said runner, said seats being positioned respectively beyond the adjacent end of the runner into which the link is automatically shiftable in one direction or another.

11. In a device of the character described, in combination, an elongated guideway having opposed edge contact surfaces and a runner having opposed channels for the reception of said edge contact surfaces, said channels each having bottom surfaces for engagement with said guideway edge contact surfaces and being convexed transversely thereof and longitudinally convexed throughout their longitudinal extent.

12. In a device of the character described, in combination, an elongated guideway having opposed edge contact surfaces and a runner having opposed channels for the reception of said edge contact surfaces, said channels each having bottom surfaces for engagement with said guideway edge contact surfaces and being convexed transversely thereof and longitudinally convexed throughout their longitudinal extent, said runner having a plurality of point contact surfaces positioned for contacting with other surfaces of said guideway.

13. In a device of the character described, in combination an elongated guideway and a securing runner mounted upon said guideway for movement therewith, said runner having similar laterally opposed longitudinally and transversely curved edge contact faces extending longitudinally of the runner and contacting with said guideway and cooperating therewith to prevent binding between the guideway and runner.

14. In a device of the character described, in combination, an elongated guideway and

a traveler mounted upon said guideway for movement therealong, said traveler having similar laterally opposed longitudinally and transversely curved edge contact surfaces extending longitudinally thereof for contacting with said guideway, said contact faces each being curved throughout the longitudi-

nal extent thereof whereby said faces engage simultaneously at points intermediate the ends thereof with the companion contact faces of the guideway when said slide is tilted or rotated edgewise to any possible extent. 10

In testimony whereof I affix my signature.
PRESCOTT C. WILSON.
